US0D1023265S

(12) **United States Design Patent** (10) **Patent No.:** **US D1,023,265 S**
(45) **Date of Patent:** **** Apr. 16, 2024**

(54) **ELECTRICALLY POWERED AIR TREATMENT DEVICE**

F24F 13/20; F24F 6/02; F24F 8/30; F24F 8/80

See application file for complete search history.

(71) **Applicant:** **Reckitt & Colman (Overseas) Hygiene Home Limited**, Slough (GB)

(72) **Inventors:** **Eleanor Bainton**, Warwick (GB); **John Mouatt**, Slough (GB); **Dafni Panagopoulou**, Slough (GB); **Blake John Parkinson**, Warwick (GB); **David Sanders**, Warwick (GB); **James Peter Spence**, Slough (GB); **Fengyang Wang**, Beijing (CN); **Christopher Brian Witty**, Slough (GB); **Cheeyong Woon**, Beijing (CN); **Jin Wu**, Beijing (CN); **George Zhang**, Beijing (CN)

(73) **Assignee:** **Reckitt & Colman (Overseas) Hygiene Home Limited**, Slough (GB)

(**) **Term:** **15 Years**

(21) **Appl. No.:** **29/779,896**

(22) **Filed:** **Apr. 21, 2021**

(30) **Foreign Application Priority Data**

Nov. 2, 2020 (EP) 008229504-0001

Primary Examiner — Gino Colan

Assistant Examiner — David O'Brien

(74) **Attorney, Agent, or Firm:** Norris McLaughlin PA

(57) **CLAIM**

The ornamental design for an electrically powered air treatment device, as shown and described.

DESCRIPTION

FIG. 1 is a front perspective top view of the electrically powered air treatment device;
FIG. 2 is a first side elevational view thereof;
FIG. 3 is a second side elevational view thereof;
FIG. 4 is a third side elevational view thereof;
FIG. 5 is a fourth side elevational view thereof;
FIG. 6 is a top plan view thereof; and,
FIG. 7 is a bottom plan view thereof.

(Continued)

The portion of the electrically powered air treatment device illustrated in broken lines form no part of the claimed design.

1 Claim, 7 Drawing Sheets
